SPLIT CENTER WINDOW JACK

Emory Harris, Miami, Fla., assignor of one-half
to Howard W. Thomas, Dade County, Fla.

Application May 17, 1944, Serial No. 535,978

3 Claims. (Cl. 304—24)

The invention relates to a window scaffold or window jack, and more especially to a foldable portable window stand.

The primary object of the invention is the provision of a stand of this character, wherein it can be readily and easily applied to single or double windows to support a workman outside of the same, without any liability of such stand becoming loose and thereby assuring safety to its user.

Another object of the invention is the provision of a stand of this character, wherein the construction thereof enables convenient folding of the same when not in use, and also is readily portable, it being placed with dispatch, and is susceptible of quick removal.

A further object of the invention is the provision of a stand of this character, wherein the same can be applied to varying sizes of windows, either of the single or double casement types, and when applied will be sturdy for withstanding a load, it being reasonably light in weight and assures a maximum speed for a workman when upon the same.

A still further object of the invention is the provision of a stand of this character, which is simple in construction, thoroughly reliable and efficient in operation, strong, durable, possessing few parts, conveniently adjusted, easily applied and removed to and from working positions, requiring little space when not in service, and inexpensive to manufacture.

With these and other objects in view the invention consists in the features of construction, combination and arrangement of parts as will be hereinafter more fully described in detail, illustrated in the accompanying drawings, which show the preferred embodiment of the invention, and pointed out in the claims hereunder appended.

In the accompanying drawings:

Figure 1 is a plan view of the stand constructed in accordance with the invention in an applied position.

Figure 2 is a side view thereof.

Figure 3 is a front elevation of the same.

Fig. 4 is a fragmentary vertical sectional view taken on the line 4—4 of Figure 1 looking in the direction of the arrows.

Figure 5 is a sectional view taken on the line 5—5 of Figure 1 looking in the direction of the arrows.

Similar reference characters indicate corresponding parts throughout the several views in the drawings.

Referring to the drawings in detail, A designates generally a double casement window of any

standard construction, B a portion of a vertical wall about the same, while C is the stand constituting the present invention and hereinafter set forth in detail.

5 The stand C comprises a pair of spaced tread wings 10, which are arranged side-by-side in the same plane with each other and their inner ends merge with a saddle extension 11 integral therewith, the latter being formed with an upwardly bent step formation creating shoulders 12 located at the inner ends of the wings 10 and placing the extension in a plane elevated with respect to the plane of such wings.

The extension 11 near opposite ends thereof 15 and parallel with the latter has formed therein rows of spaced vertical holes 13 for selectively receiving the stems 14 of a locking staple 15 of inverted substantially U-form, excepting that its closed head portion is bent over at substantially 20 right angles to the stems 14, so that the inner face of the vertical parting strip 16 of the double window frame of the casement window A will have contact with said head portion of the said staple 15, when the stand is placed upon the sill 25 area of the window with the wings straddling the strip 16 and projected exteriorly of such window. In this position of the stand the shoulders 12 of the extension 11 abut the outer face of wall B next to the sill area of the window A, while the stems of the staple 15 make contact with the inner face of such wall with the wings 10 in a 30 horizontal plane. The staple 15 is set in the extension accordingly to the thickness of the wall area next to the frame of the window A.

35 Hinged to the under sides of the wings 10 are the swingable inner prop 17 and the outer double armed latching bail 18 for the latter, the hinging being at 19, and each latching bail 18 is formed with hook terminals 20 for separably engaging 40 selected eyelets 21 formed on the prop frames 17 which are of the closed-loop type. Each prop 17 contacts with the outer face of the wall B and is latched by the bail 18 in such position, so as to horizontally prop the wings 10, and in this manner the stand is made secure in position to support a load outside of the window A, as will be clearly apparent from Figures 1, 2 and 3 of the drawings. If the stand is used on a single window then the wings 10 are in a non-straddling 45 position, as there is no strip 16 present in this type of window, yet the stand will be firmly held in place through the action of the shoulder and staple arrangement hereinbefore described.

50 On detaching the latching bails 18 from the props 17 and removal of the staple 15 from the

extension the stand can be taken out of the window A and folded into compact form.

The compact form enables the stand to be stored in the least possible space when not in use or to be transported, from one locality to another, either by vehicle or hand carriage thereof.

The arms of the bails 18 are inherently springy for the separable connection of the hook terminals 20 in the eyelets 21.

The staple 15 functions as a blocking medium for the stand in fastening the latter in place upon the sill area of a window.

What is claimed is:

1. A stand of the kind described, comprising a stepped extension, spaced wings formed integral with the extension at the lower portion of the step thereof, a substantially U-shaped blocking staple having its head portion bent at substantially right angles to the stems thereof adjustably fitting the extension, a releasably latched prop at the under side of each wing.

2. A stand of the kind described, comprising a stepped extension, spaced parallel wings formed integral with the extension at the lower portion of the step thereof, a substantially U-shaped blocking staple having its head portion bent at substantially right angles to the stems thereof adjustably fitting the extension, a releasably latched prop at the under side of each wing, and means on each wing for releasably latching the prop common thereto.

3. A stand of the kind described, comprising a stepped extension, spaced wings joining the extension at the lower portion of the step thereof, a blocking staple adjustably fitting the extension, a releasably latched prop at the under side of each wing, means on each wing for releasably latching the prop common thereto, and connections hinging the prop and means to the respective wings.

20

EMORY HARRIS.
